UNITED STATES PATENT OFFICE.

BYRON A. SHAMMO, OF NEW YORK, N. Y.

SHOE-FASTENER.

1,368,847.

Specification of Letters Patent. Patented Feb. 15, 1921.

Application filed May 8, 1920. Serial No. 379,874.

To all whom it may concern:

Be it known that I, BYRON A. SHAMMO, a citizen of the United States, and a resident of New York city, borough of Manhattan, in the county of New York and State of New York, have invented a new and Improved Shoe-Fastener, of which the following is a full, clear, and exact description.

This invention relates to fastening devices which may be used in a number of places but is especially adapted for use with shoes. One of the objects of the invention is to provide a fastener for shoes or other articles which may be easily interlocked or disengaged manually but which will not accidentally become disengaged.

Another object of the invention is to provide a fastener for shoes and a lock wherein a proper clasping action is secured when first used and means are presented which will permit a readjustment of the parts to maintain a desired position of the garments fastened and which will thereby automatically take up any stretching or distending of the material of the article.

A still further object of the invention is the arrangement of a number of plates and interlocking members which utilize extensions or spurs for clamping the interlocking parts in place, the arrangement being such that the clamping spurs overlap metal members and thereby will not injure the article to which the fastener is applied.

In the accompanying drawings:

35 Figure 1 is a side view of a shoe with fastening means embodying the invention shown applied thereto.

Fig. 2 is a fragmentary sectional view through Fig. 1 on line 2—2, the same being 40 on an enlarged scale.

Fig. 2^a is a top plan view of a retaining plate shown in Fig. 2.

Fig. 2^b is a top plan view of a clamping plate shown in Fig. 2.

45 Fig. 3 is a plan view of a combined hook and plate providing certain features of the invention.

Fig. 4 is a plan view of the blank of the retaining plate.

50 Fig. 5 is a fragmentary view similar to the upper part of Fig. 1 but showing a slight modified form of the invention applied thereto.

Fig. 6 is a sectional view through Fig. 5 on line 6—6, the same being on an enlarged scale.

Fig. 7 is a plan view of a blank disclosing a retaining structure embodying certain features of the invention.

Fig. 8 is a blank of an interlocking plate.

Fig. 9 is a sectional view similar to Fig. 6 but showing a further modified form of the invention.

Referring to the accompanying drawings by numeral, 1 indicates a shoe of any desired kind provided with the fastening members 2 to hold the flaps 3 and 4 of the shoe together when interlocked. The fastening features 2 comprise what may be termed a hook structure 5 and an interlocking structure 6 for holding the flaps 3 and 4 together.

In Figs. 2 to 4 will be seen detail views showing the construction of the fastener. As indicated in Figs. 2 and 2^b, a clamping plate 7 is provided having a number of spurs 8, an aperture 9 and an opening 10 in a reduced portion 11. It will be noted that the plate 7 is made substantially round at one end and provided with an elongation 80 in which the opening 10 is positioned, the exact shape being immaterial but it is desired to make as neat and pleasing a shape as possible. The opening 10 is provided with an enlarged end merging into a small 85 neck 12 designed to receive a hook hereinafter fully described. The opening 9 is adapted to receive what may be termed a covering cap 13 which overlaps part of plate 7, as shown in Fig. 2, and is hollow. A depending annular flange 14 is provided on the bottom part of the cap, said flange 90 extending through the opening 9 in plate 7 and also through the opening 15 in plate 16, said flange carrying an interlocking bar 17, preferably arranged nearer the bottom of the flange than the top, so that the hook 18 with its knob 19 may more readily interlock therewith. As indicated in Fig. 2, the spurs 8 during application are forced 100 through the leather of the shoe and then bent over and clamped tightly against plate 16. Plate 16 is provided with an opening 15 registering with opening 9 and also with an opening 20 registering with opening 10. 105 Coacting with the bar 17 and associated

parts is the hook structure 5 which is formed with a retaining plate 21, shown in the drawing as being a circular disk, but it could, of course, be formed in some other 5 shape. The plate 21 is provided with a pair of pressed out sections 22 which clamp the body 23 of the hook 18 rigidly to the plate 21, thus obviating the use of solder or other securing means. If desired, after the 10 parts have been assembled as shown in Fig. 3, the parts 22 could be pressed down somewhat so as to bend part of the body 23 into the openings from which sections 22 have been pressed though, ordinarily, this 15 is not necessary. A retaining or clamping plate 24 is provided for holding plate 21 in position, said clamping plate having a number of spurs 25 adapted to pass through part of the shoe and to overlap plate 21. 20 This plate is provided with an opening 26, through which the hook extends, as shown in Fig. 2.

In Figs. 5 to 8 will be seen a slight modified form of the invention, in which 25 the hook structure 5 is the same as shown in the preferred form except the hook 18' is bent over at a sharp angle for engaging the turned up flange 27 on the retaining or interlocking plate 28. Coacting with the 30 plate 28 is a plate 29 similar to the plate 7 except that the aperture 9 is eliminated and the central part of the plate is bowed or bushed at 30 so as to provide a form of hood for the hook 18' and at the same time 35 present a pleasing appearance.

In Fig. 9 will be seen a further modified form of the invention which is similar to the structure shown in Fig. 6 except for a few slight changes which in some respects 40 will simplify the construction. In this form of the invention, the plate 28' is a circular disk and is provided with an opening 31, through which the end of hook 18' passes while plate 29' is provided with spurs 29'' 45 for clamping the parts together. The openings 10 and 20 in this form of the invention are eliminated so that the hook 18' can interlock only with one member, namely, with the flange 27. In the construction shown in 50 Figs. 2 and 6, the hook may interlock with the bar 17 or the flange 27, as the case may be or may be adjusted so as to interlock with plates 7 and 16 in the apertures 10 and 20. A suitable aperture in both cases is 55 provided in the leather of the shoe so that the hook may pass freely through the openings in the respective plates. In many cases, the flaps 3 and 4 of the shoe are as tight as desirable when the hook 18 is engaging bar 17, for instance; but, after the shoe has been worn for some time the leather stretches and, consequently, there is a looseness between the flaps. To take care 60 of this, the hook 18 is disengaged from bar 17 and interlocked with the plates 7 and 16

by having the hook extend through the openings 10 and 20 and then moved into the slots 12 of said plates. This will cause an effective interlocking of the parts and the fastening of the flaps together at a new point 70 which will cause the shoes to again snugly fit the person wearing the same.

In operation, after the parts have been arranged correctly in position on the shoe and it is desired to fasten the flaps 3 and 4 75 together, the part carrying the bar 19 is turned, or rather rotated, so that the hook 18 may enter the opening beside the bar 17 in such a manner that the plane of the hook will be parallel to the bar 17, and after the 80 knob 19 has moved a sufficient distance into the cap 13, the parts are rotated back to their former position and the hook will be interlocked with the bar. By forming the device so that this is necessary in interlocking or 85 disengaging the part, the hook will not ordinarily become accidentally disengaged by any looseness of the parts but will require a positive disengaging movement. In interlocking the structure shown in Figs. 6 and 8, 90 the ordinary interlocking movement is utilized and the parts drawn sufficiently in an overlapped position to allow the hook to move through the opening in plate 28 and then back to an overhanging position. 95

What I claim is:

1. A fastener for shoes comprising a hook structure and an interlocking structure, said hook structure being formed with a hooked member and said interlocking 100 structure being formed with a socket having a transverse bar therein, the shape of the socket being such that the hooked member is easily removed by turning the same so that the plane thereof will be substantially parallel to the bar.

2. A fastener for shoes comprising an interlocking structure formed with a pair of interlocking clamping plates having an aperture therein, a cap snugly fitting in 110 said aperture, said cap having an annular dependent flange projecting through said aperture, a bar extending from one side of said flange to the other centrally thereof and a coacting hook for interlocking said bar. 115

3. A shoe fastener comprising an interlocking structure provided with a clamping plate, a retaining plate, a hollow cap, and a bar extending through the hollow cap, said cap fitting into said plates and said clamping plate having spurs interlocking and overlapping the retaining plate and a hook coacting with said bar for holding the parts of the article together. 120

4. A shoe fastener comprising an interlocking part and a hook structure, said hook structure being formed with a plate, a hook shaped member secured thereto and a clamping plate having an opening for accommodating said hook shaped member, and 125 130

- a plurality of spurs overlapping said plate for locking the same in position on a shoe.
5. In a fastener for shoes, an interlocking member secured to one part of the shoe and a hook structure secured to the other adapted to interlock with the interlocking structure, said hook structure comprising a disk provided with a pair of pressed out sections, a hook shaped member having a body 10 clamped to the disk by said pressed out sections, and a knob at the end for normally holding the parts in interlocked relationship when in operative position, and a clamping plate having an opening through which the 15 hook shaped member extends, and a plurality of spurs adapted to extend through part of said shoe and overlap said disk.
6. A fastener for shoes comprising an interlocking member and a hook structure, said interlocking member being provided 20 with a pair of plates having registering openings merging into small necks and a pair of large registering openings, a cap fitting into said large registering openings provided with a bar, a hook member forming part of said hook structure adapted at one time to interlock said bar and at another time with said plates in said neck opening. 25

BYRON A. SHAMMO.
